OIL TANK.

No. 307,689.

Patented Nov. 4, 1884.

9901
X 9916Attest
E. M. Hunter
George E. Hammel.

1. The herein-described method of preventing explosions in oil-tanks, which consists in forcing steam into the tank above the oil, whereby all of the accumulated explosive gases are saturated with moisture and rendered non-explosive, substantially as and for the purpose specified.

2. The herein-described method of preventing explosions in oil-tanks, which consists in forcing steam into the tank above the oil, whereby all of the accumulated explosive gases are saturated with moisture and rendered non-explosive, and, finally, expelling said mixture of steam and gases from the tank, their place being supplied by steam alone, substantially as and for the purpose specified.

In testimony of which invention I hereunto set my hand.

Inventor
Russell Thayer
By authority
R. Thayer

UNITED STATES PATENT OFFICE.

RUSSELL THAYER, OF PHILADELPHIA, PENNSYLVANIA.

OIL-TANK.

SPECIFICATION forming part of Letters Patent No. 307,689, dated November 4, 1884.

Application filed May 28, 1884. (No model.)

To all whom it may concern:

Be it known that I, RUSSELL THAYER, of the city and county of Philadelphia, and State of Pennsylvania, have invented a new and useful Improvement in Oil-Tanks, of which the following is a specification.

My invention has reference to storage-vessels for storing volatile liquids in bulk; and it consists in a tank having means, substantially as hereinafter set forth, to create a forced displacement of the accumulated volatile and explosive hydrocarbon gases in the upper part of the oil-storage tanks by the introduction of steam under more or less pressure, which steam saturates the explosive vapors with moisture, rendering them non-explosive; further, in ejecting the mixture of saturated hydrocarbon vapors and steam from the reservoir or storage-tank by forcing therein an excess of steam, all of which is fully set forth in the following specification, and shown in the accompanying drawings, which form part thereof.

The large iron tanks in which petroleum-oil is stored very frequently explode during thunder-storms, and it has always been supposed that the explosion was caused by the tanks being struck by lightning. This, however, is not the case in most instances, and after a careful investigation of the subject I discovered that the explosion is caused not by the lightning itself, but by the concussion produced by the thunder caused thereby, the concussion of the atmosphere exploding the oil-tanks in the following manner: Petroleum is a mixture of a great number of paraffines differing greatly in volatility. Of these methane, ethane, propane, and quartane are gaseous at ordinary temperatures, while quintane vaporizes at 86° Fahrenheit, sextane vaporizes at 154° Fahrenheit, septane at from 198° to 201° Fahrenheit, and the other constituents require a higher temperature before becoming gaseous. Now, all these hydrocarbons, when mixed with a small quantity of atmospheric air, become highly explosive, and those enumerated above require but a small amount of heat to cause them to ignite. In the tanks used for storing oil the above and other highly-explosive gases accumulate under the roof of the tank above the oil. When an electrical disturbance of the atmosphere occurs and

a severe flash of lightning takes place, a very powerful concussion is produced, and this is communicated instantly to the gases in the oil-tank above the oil, producing increased heat in the already-heated gases therein and causing them to explode, thus blowing up the tank and setting fire to the oil. This can be entirely avoided by removing the dangerous gases as rapidly as they are produced, and the proper way of doing this is to thoroughly ventilate the space above the surface of the oil, or any other places where the gases could possibly accumulate. This can be done by forcing steam under pressure into the tank above the oil, and preferably in such a manner as to eject all of the explosive gases after saturating the same, and rendering them non-explosive and incapable of ignition except by great heat. It is desirable that the steam be forced in at the top and gases ejected on or near the oil-level, or vice versa. If found desirable, the ejected gases may be condensed and the oil thus saved, which would otherwise be lost.

In the drawings, Figure 1 is a sectional elevation of an oil-tank embodying my improvements. Fig. 2 is a plan view showing three tanks in which the explosive gases are all condensed by the same condenser.

The condensation of the volatile and explosive gases may be produced whether steam be used or not. For instance, air may be forced in to eject the gases; or they may be sucked off and forced through a condenser; or steam may be forced into the tank, and the mixture of steam and gas passed into the condenser.

A is the tank, and B is the cover, said parts being commonly made of sheet-iron.

C are ventilating-apertures arranged in the top of the tank and just above the level of the oil, substantially as shown.

D is a suction-pipe which connects with a boiler, J, by a pipe, L, supplied with a valve, K.

F is the discharge-pipe for the oil from the tank.

G is a stand-pipe or water-column, having valved overflow-pipe g, and connecting with a source of water-supply, as pump I. The bottom of the stand-pipe G is connected to the bottom of the tank A by a pipe H.

H' is a condenser, and I' a receiving-tank.

The operation is as follows: Some water K is forced into the bottom of tank A, and upon this the oil J is placed in the usual manner. If there is not sufficient oil to fill tank A up to the ventilating apertures C, more water is forced into the pipe G and also tank A. By this means the oil is made to rise to the desired height, so that there shall be a minimum space in the tank above the oil, to the end that the volatile gases given off shall be readily removed by allowing steam to pass into the tank by pipes L and D, as indicated by arrows in Fig. 1, first saturating the gases and rendering them non-explosive, and then ejecting them from the apertures C. If it be desired to empty the tank or remove any part of the oil, water is forced into the tank, as before, and the discharge-pipe F is opened, allowing the oil to run off. The column of water in the pipe G up to the overflow g is of such a height as to balance the oil in the tank when its height is sufficient to just cover the outlet F. By keeping the pipe F and overflow open and pumping in fresh water the oil will continue to run out until the water in pipe G and tank A is on the same level, when the last portion of oil may be expelled by closing the overflow g, and thereby increasing the height of the stand-pipe. With this apparatus the height of oil in the tank is always the same, and the oil is partly cooled by the water upon which it rests. If desired, the pipe D may communicate with a suction-fan, E, and the gases may be sucked out of the tank. When not in use, the valve M may be closed to prevent the steam from pipe L passing through the fan. The steam may be used by itself or in conjunction with the air-draft, if desired.

If desired, a large number of tanks may be purified by a single pump or exhauster, E, as indicated in Fig. 2, in which the pipes D from

tanks may connect with a single main, D', common to all, and the vapors thus extracted may be condensed in a single condenser, H', and then collected in a tank, I', if desired.

45

While I have shown the apparatus as employing an exhauster, it is self-evident that a force or pressure blower might be used, and the air driven in by pipe D or apertures C, and then allowed to escape or be collected, and then condensed as before.

The locations of the pipe D and apertures C are immaterial to my invention, for they might all be in the tank or all in cover, if desired; but I prefer them to be arranged as shown.

Having now described my invention, what I claim as new, and desire to secure by Letters Patent, is—

1. The herein-described method of preventing explosions in oil-tanks, which consists in forcing steam into the tank above the oil, whereby all of the accumulated explosive gases are saturated with moisture and rendered non-explosive, substantially as and for the purpose specified.

2. The herein-described method of preventing explosions in oil-tanks, which consists in forcing steam into the tank above the oil, whereby all of the accumulated explosive gases are saturated with moisture and rendered non-explosive, and, finally, expelling said mixture of steam and gases from the tank, their place being supplied by steam alone, substantially as and for the purpose specified.

In testimony of which invention I hereunto set my hand.

RUSSELL THAYER.
